LAKEWOOD, OHIO

VIBRATOR

Application filed June 28, 1924. Serial No. 722,971.

This invention relates to vibrators of the fluid operated reciprocating plunger type and is an improvement over the vibrator covered by my co-pending application Serial No. 5 628,158, filed April 2, 1923.

This invention is designed particularly for use in foundries for cleaning sand from castings by the method disclosed in my application Serial No. 722,970, of even date herewith, 10 and has for its objects to provide a fluid operated vibrator which is effective in carrying out the operations above referred to and in which the impact of the piston in one direction is effectively cushioned without imparting vibrations to the cylinder casing or supporting frame.

It has been found that the castings may be cleaned much more rapidly by eliminating the vibrations due to impact of the piston or 20 striker against the end of the cylinder on its return stroke and additionally it has been found that a vibrator such as disclosed herein may be used in forming sand molds. By imparting vibrations to a mold filled with 25 loose sand by a rapid succession of sharp taps or percussive impacts in one direction only, the same may be caused to quickly settle and pack in the mold.

With the above and other objects in view, 30 the invention may be said to comprise the device as illustrated in the accompanying drawings hereinafter described and particularly set forth in the appended claims, together with such variations and modifications thereof as will be apparent to one skilled in the art to which the invention appertains.

Reference should be had to the accompanying drawings forming a part of this 40 specification in which Fig. 1 is a central longitudinal section through the vibrator; Fig. 2 is an end elevation of the vibrator with a portion broken away to show the exhaust ports in section; Fig. 3 is a side elevation of 45 the piston; Fig. 4 shows the vibrator arranged in horizontal position with a casing held against the percussion member; Fig. 5 shows the vibrator shown in vertical position with the vibrator bearing against the under- 50 side of a mould supporting table.

Referring to the accompanying drawings, the vibrator casing consists of an outer cylindrical casing 1 which is open at one end and an inner cylinder 2 which is adapted to be inserted into the outer casing through the open end thereof, the rear end of the cylinder 2 being closed by an end plate 3 which bears against the integral rear wall of the outer casing, and the outer end of the inner cylinder being closed and held in place by means of a front closure member 4 which has a portion that fits within the end of the outer casing and has flanges 5 overlying the edge thereof, the flanges 5 being secured to the casing by means of tap bolts 6. The inner cylinder is held against rotative movement in the casing by means of a screw stud 7 which is screwed into a threaded opening in the outer casing and projects into an opening in the inner cylinder. Extending through the closure member 4 at the center thereof is a percussion member 8 which fits in a central opening in the head 4, projects beyond the inner face thereof to receive the impact of the piston and is provided with an enlarged head 9 against which the casting 10 to be cleaned is held as shown in Fig. 4. When the vibrator is used for compacting the sand in a mold, the cylinder is mounted in vertical position beneath a mold supporting table 11 as shown in Fig. 5 with the percussion member bearing against the underside of the table. Within the cylinder there is mounted a piston or striker 12 which has two peripheral grooves forming three spaced peripheral flanges 13, 14 and 15 which have a sliding fit within the inner cylinder 2. Between these flanges the annular grooves form with the wall of the cylinder two annular chambers 17 and 18. The chambers 17 and 18 are separated by the 55 central flange 14 which is imperforate, the chambers 17 and 18 being in communication with the interior of the cylinder at opposite ends of the piston through annular rows of ports 19 and 20 through the flanges 13 and 15. An air inlet chamber is formed in the wall of the inner cylinder by a bore 21 extending longitudinally from the forward end, the end of the bore being closed by a screw plug 22. The inlet chamber 21 communicates 60 65 70 75 80 85 90 95 100

with the interior of the cylinder through two longitudinally spaced ports 23 and 24 which are so spaced that as the piston reciprocates they are alternately opened and closed by the flanges 13 and 15 and are placed alternately 5 into communication with the annular chambers 17 and 18 to move the piston in opposite directions. Air under pressure is supplied to the inlet chamber 21 through an inlet pipe 10 25 which extends through the wall of the casing and communicates with the chamber, a suitable valve 26 being provided in the pressure line to control the admission of pressure to the cylinder. An annular exhaust 15 chamber 27 surrounds the inner cylinder 2 substantially midway between the ends thereof, the chamber 27 being formed by complementary grooves formed in the inner surface of the outer casing and the outer surface 20 of the inner cylinder. Communication between the interior of the cylinder and the exhaust chamber 27 is established through either of two parallel circumferentially extending rows of exhaust ports 28 and the air 25 escapes from the exhaust chamber through an exhaust pipe 29 which is attached to the outer casing and communicates with the exhaust chamber adjacent the ports 28. The two rows of ports 28 are so positioned that 30 as the piston moves past the ports pressure is exhausted alternately from opposite sides of the piston so that as pressure is being admitted to one side of the piston, air is permitted to escape from the opposite side. 35 Once the piston is started it will continue to reciprocate as long as pressure is supplied to the cylinder due to the automatic reversal of pressure by the movement of the piston past the ports. The reciprocating movement of the piston is so rapid that in normal 40 operation of the vibrator the leakage of air as the piston passes the central point is very slight.

A cushioning plunger 30 is mounted within 45 the rear end portion of the cylinder, the cushioning plunger 30 having a sliding fit within the cylinder which is counterbored to provide a shoulder 31 to limit the inward movement of the plunger. The plunger 30 is normally held against the shoulder 31 by fluid 50 pressure supplied through an inlet pipe 32 which communicates with the chamber 33 between the plunger 30 and rear end plate 3 through a port 34 in the cylinder 2 adjacent 55 the end plate 3. The plunger 30 is cup-shaped and has a rearwardly extending skirt or flange 35 which serves to center and guide the plunger. A body 36 of a suitable liquid lubricant such as oil fills or partially fills the 60 chamber 33 and this liquid together with the air serves to produce a cushion effect as the plunger 30 moves toward the plate 3. The movement of the plunger 30 under the impact of the piston is cushioned by the body 65 of air and oil under pressure, and the in-

creasing resistance to movement of the plunger due to the liquid and air within the chamber brings the cushioning plunger to a full stop after a slight movement thereof and before it actually impinges against the rear 70 end plate so that the impact of the piston is completely absorbed and not transmitted to the cylinder 1. It should be noted that as the plunger moves toward the rear of the casing the skirt or flange 35 passes across the 75 port 34 thus reducing the size of such port and impeding the escape of fluid from the space between the end of the plunger and the cylinder.

The plunger 30 fits in the cylinder loosely 80 enough to permit a slight leakage of air past the same into the space behind the piston 12 and this leakage serves, when the vibrator is mounted in horizontal position, to shift the piston and hold it in its forward position in 85 engagement with the percussion member 8 whenever the vibrator is stopped by shutting off the valve 26, so that the piston cannot be stopped at dead center position. When mounted in vertical position as shown in Fig. 90 5 the weight of the piston 12 overcomes any pressure due to leakage so that the piston, whenever the operating pressure is cut off, drops by gravity to the lower portion of the cylinder in which position the inlet port 24 95 communicates with the underside of the piston and the upper side thereof is open to the exhaust ports so that the piston will always be operated when the operating pressure is admitted to the cylinder. The cushioning 100 device also serves to lubricate the vibrator since in the operation thereof a sufficient amount of oil will be forced past the plunger 30 into the main chamber of the piston to properly lubricate the piston.

In the operation of the vibrator the piston 105 rapidly reciprocates and impinges alternately against the percussion member 8 and cushioning plunger 30. The vibrations produced by impact against the percussion member are transmitted to the work while the vibrations due to impact against the cushioning plunger are entirely absorbed and dissipated by the fluid pressure and its cushion action. Thus 110 all vibrations except those produced by impact against the percussion member are eliminated so that vibrations are transmitted to the work, either the casting to be cleaned or the mold in which sand is to be packed in one direction only.

It will be understood that when in the specification and claims I refer to the mold supporting table, I mean a table for supporting a mold flask, a core box or any container 115 in which sand or other material is to be compacted.

While I have disclosed my vibrator with 120 relation to a molding machine and a machine for removing sand from castings, I do 125

not thereby limit my invention to such uses only.

Having described my invention, I claim:

1. A vibrator comprising a cylinder having a reciprocating piston therein and provided with inlet and exhaust ports so positioned with respect to the piston as to be alternately opened and closed by the piston as it reciprocates, and means forming a fluid cushion for the piston at one end of its stroke, said cushioning means being supplied with fluid under pressure independently of the piston, and adapted to permit a slight leakage of pressure into the piston chamber at one side of the piston to prevent the same from stopping in a dead center position with respect to said ports.

2. A vibrator comprising a cylinder having a reciprocating piston therein and provided with inlet and exhaust ports so positioned with respect to the piston as to be opened and closed by the piston to reverse the direction of movement thereof, and a cushioning device at one end of the cylinder comprising a plunger slidable in the cylinder and means for admitting pressure between the plunger and end wall of the cylinder, said plunger permitting leakage of pressure into the main chamber of the cylinder to prevent the piston from stopping in a dead center position with respect to said ports.

3. A vibrator comprising a cylinder having a reciprocating piston therein and means for supplying fluid thereto to operate the piston, said cylinder having a percussion member at one end to receive the impact of the piston, a plunger slidably mounted in the opposite end of the cylinder, means for limiting the inward movement of the plunger, means for maintaining fluid pressure between said plunger and the end of the cylinder, and means for impeding the escape of fluid from the space between the plunger and the adjacent end of the cylinder to prevent jarring impact against said end.

4. A vibrator comprising a cylinder having a reciprocating piston therein and means for supplying fluid pressure thereto to operate the piston, and means for cushioning the stroke of said piston in one direction comprising a plunger slidably mounted in an end portion of the cylinder and movable toward and from the adjacent end wall, means for limiting the inward movement of the plunger, and means including a port opening into the cylinder adjacent said end wall for supplying fluid pressure between the plunger and adjacent end wall toward which it moves, said plunger having a part adapted to move over and restrict said port as the plunger approaches said end wall.

5. A vibrator comprising a cylinder having a reciprocating piston therein and means for supplying fluid pressure thereto to operate the piston, and means for cushioning the

stroke of the piston in one direction, comprising a cup shaped plunger slidably mounted in the end of the cylinder and movable toward and from the end wall of the cylinder, said plunger having a cylindrical flange projecting toward the adjacent end wall of the cylinder, means for limiting the inward movement of the plunger, and means for supplying air under pressure to the chamber formed between the plunger and end wall of the cylinder comprising a port in the cylindrical wall of the cylinder adjacent the end wall over which the edge of said flange moves as it approaches said end wall.

In testimony whereof, I hereunto affix my signature.

JOHN T. STONEY.
